UNITED STATES PATENT OFFICE.

LUCIEN A. DEXTER, OF GRAND RAPIDS, MICHIGAN.

LOCK.

Application filed September 17, 1923. Serial No. 663,067.

To all whom it may concern:

Be it known that I, LUCIEN A. DEXTER, a citizen of the United States of America, residing at Grand Rapids, in the county of Kent and State of Michigan, have invented certain new and useful Improvements in Locks; and I do hereby declare the following to be a full, clear, and exact description of the invention, such as will enable others skilled in the art to which it appertains to make and use the same.

This invention relates to locks of the general type and character shown in United States Letters Patent No. 1,399,538, issued Dec. 6, 1921, and is directed to several improvements in construction thereover. Among the objects and purposes of the invention is the provision of novel means for a more ready assembly of the parts in manufacturing the lock. A further and more important object of the invention is the provision of means whereby, irrespective of the width of the door with which the lock is used, a single size of lock construction is universally adapted for use therewith, making it unnecessary to manufacture several sizes with the consequent production and upkeep of dies for the different sizes. Still further objects are to provide a lock which is very easily and readily installed in a door, which is shaped and formed so as to snugly fit in the opening bored in the door for its reception, there being no leeway for the movement of the lock in the opening in the door made for its reception and at the same time the construction is simplified and a sufficient throw for the lock bolt provided together with provision made for keeping the lock bolt in either outer operative or inner inoperative positions whenever moved to either position. These features, as well as many others not specifically stated at this time will appear fully and in detail as understanding of the invention is had from the following description, taken in connection with the accompanying drawings, in which, Fig. 1 is a vertical section through a door with the lock installed therein and in retracted inoperative position.

Fig. 2 is a like view showing the lock bolt in outer operative locking position.

Fig. 3 is a transverse section through the door and lock showing the operating handle connected therewith.

Fig. 4 is a perspective view of one half of the barrel or enclosing casing for the lock mechanism.

Fig. 5 is a perspective view of the two parts of the lock bolt operating mechanism which are adapted to be either key operated or operated by a knob or handle.

Fig. 6 is a perspective view showing the parts of the lock bolt separated, and

Fig. 7 is a perspective view of the operating knob or handle used with the lock.

Like references refer to like parts in the different figures of the drawing.

In the construction of the lock, a barrel is made to enclose the lock mechanism, comprising two identical parts formed from sheet metal, each including a length of metal formed into semi-cylindrical shape as indicated at 1. At a point between the ends of the member 1 a circular opening 2 is cut in the side thereof which is surrounded by an inwardly extending circular flange 3 to serve as bearings for the lock operating parts hereafter described. In addition, at both the upper and lower edges of the member 1 for a portion of its intermediate length, the metal is pressed, as indicated at 4 whereby when two of the members 1 are placed together, as in the completed lock, an upper and a lower elongated groove or trough is formed to provide space for a part of the lock mechanism as it is operated, as later set forth.

Two of the members 1 are placed together with their edges in contact, making a substantially cylindrical barrel and at one end a cap 5 is used to place over the ends of the members 1 to hold them together. The method of attaching this cap is the same as that shown in the patent above noted and need not be further described or illustrated in connection with the present invention. Similarly, the opposite ends of the members may be covered and held in place by a cap 6 which is attached to a face plate 7, an opening being made through both the end of the cap and the plate and the connection between them made by tangs 8 of

metal from the plate passing through the opening in the cap and clinching over against the inner side thereof.

The openings through the cap and plate 7 permit the passage of the locking bolt 9 therethrough. Said bolt is formed of a length of rod, and at its inner end reduced in size to make a short cylindrical projection, this projection being slotted lengthwise and the slot carrying into the body of the bolt 9 for a distance, as indicated at 11, the smaller projection at the inner end of the bolt being divided into two parts 10, as shown. A small opening 12 is made through both parts 10 (see Fig. 6). A washer 13 with a central opening 14 through it is passed over the parts 10 and at diametrically opposed points notches 14^a of the same width as the slot 11 are cut which are in communication with the opening 14.

An irregularly shaped member 15 made from flat metal is used in conjunction with the bolt 9 it, on its lower side being formed with a downwardly projecting part 15^a. An arm 16 integral with the part 15 extends away from the bolt and at its free end is turned downwardly and somewhat enlarged as indicated at 17, an opening 18 being made through the front end of the member 15 and a like opening 30 through the part 17. A leaf spring 19 is secured at one end to the forward portion of the member 15 and is of a width to freely pass into the slot 11, bearing against the bolt 9 at the bottom of the slot, a pivot pin 20 passing through the openings 12 and 18 in the parts 10 and member 15 and with the spring 19 placed under tension as this connection of the bolt and member 15 is made. It is apparent that the member 15 with its arm 16 occupies the intermediate portion of the barrel between the grooves or troughs made by the recesses pressed at 4.

An operating device for the lock bolt is used comprising two parts, each pressed from sheet metal. One of said parts includes an annular flange 21 projecting from an integral cup portion 22 in the closed end of which a squared opening 23 is made. In the flange at diametrically opposed points small openings 24 are made as shown. The other part includes an annular flange 25 integral with a similar cup portion 26. From the flange at diametrically opposed points two pins project, being secured permanently to said flange. Each pin includes a section 27 having a diameter slightly less than the diameter of the hole 30, and a smaller section extending from the first section, as indicated at 28 and of a size to freely enter the openings 24 in flange 21. The outer diameter of the cup portions 22 and 26 is such that the same are received in the openings 2 in members 1 and rotatably mounted in the flanges 3. The closed end of the cup 26 has

openings 29 therein for the reception of end projections on a key for turning the operating device when it is assembled in the lock. In the assembly, the end 17 of arm 16 is put over one of the pins, passing over the larger section 27 thereof, the cup portions are entered into the openings 2 and the two members 1 brought together whereupon the reduced sections 28 of the pins enter the openings 24 in flange 21. The cup portions 22 and 26 are formed with annular shoulders to bear against the inner ends of the flanges 3. The caps 5 and 6 are then attached and the lock assembly is complete.

In installing the lock in a door, shown at 31, an opening 32 is bored inwardly from the free vertical edge of the door a distance somewhat greater than the length of the lock barrel and of a diameter equal to the distance across the lock barrel where the portions 4 are pressed therein. A second opening of smaller diameter, at 33, is bored transversely through the door at the point where the operating parts for the lock are located so that the cup portions 22 and 26 are in direct alignment with said opening 33. The plate 7 is securely attached by means of screws, the door being cut away sufficiently to make a flat recess to receive the plate. An escutcheon plate 34 of any desired design is secured to the inner side of the door by screws, said plate carrying a suitable square bar 35 which passes through the plate and is rotatably mounted therein, being equipped with an operating knob or handle 36 at its outer end which may be manually operated to turn the bar 35. The bar 35 passes through the opening 23 in the cup portion 22. It will be apparent that the doors to which this lock may be applied may be of many different thicknesses, the bar 35 serving to operate the operating device either when it is barely through the opening 23 or if it is projected therethrough substantially to the closed end of the part 26, or at any position between these two extreme positions.

On the outer side of the door a like escutcheon plate 34^a is secured by screws or like fastenings, in which a key guide 37 is rotatably mounted and through which a key may be passed to engage in the openings 29 to operate the lock from outside the door.

With the lock bolt in the position shown in Fig. 1, the bolt may be projected to the position shown in Fig. 2 by operating the knob 36, or by a key passed through the guide 37, depending upon which side of the door the operator is located at the time of operation. The two parts of the operating device being connected by the pins turn together and the member 15 with its arm 16 is moved longitudinally, as is evident, projecting the lock outside the door to engage with a suitable socket in the floor casing for

the bolt. The retraction of the bolt from the position shown in Fig. 2 to the position shown in Fig. 1 is effected in the same manner by turning in the opposite direction. The spring 19 serves to hold the pivot pin 20 down so that it cannot readily elevate above the line joining the centers of the two pins 28 and thereby precludes pushing in of the lock bolt or its accidental partial movement outward, both of which are undesirable. In the movement of the lock bolt, the arm 16 is elevated so that it enters the upper groove made by the parts 4, such parts being provided only for the purpose of clearance for the said arm. They are provided on both sides in order that the lock shall be adapted for use with doors swinging from either edge, for ease of assembly in that particular care does not need to be exercised in putting the parts together, and in order that one die will serve for both halves of the barrel. The assembly of the lock is especially easy, no machine operations being required, the parts fitting together readily by hand. The part 15^a rides on the inner side of the barrel when the bolt is projected and keeps it straight. In every way the construction is particularly practical and economical to manufacture. The ribs made by the projecting portions 4 bear against opposite sides of the opening 32 and hold the lock against movement. Of course, if desired, such portions need not be pressed from the metal but can be cut away leaving slots for the passage of the arm 16, but the structure described is preferred. The invention is defined in the appended claims and is to be considered as comprehending all forms of structure coming within the scope thereof.

I claim:

1. A lock comprising a cylindrical barrel, a lock bolt mounted for projection out of one end of the barrel or retraction into the barrel, a member pivotally connected at one end to the inner end of the bolt, and a two part operating device located between the sides of the barrel and rotatably mounted therein, each including a cup-portion with an annular flange, said flanges being located in parallel relation to each other and connected together, the opposite end of the said member being connected to said operating device between said flanges near one edge of the flanges, substantially as described.
2. A lock comprising a substantially cylindrical barrel, a lock bolt mounted for projection out of one end of the barrel or retraction into the barrel, a member pivotally connected at one end to the inner end of the bolt, a two-part operating device located between the sides of the barrel and rotatably mounted therein, each including a cup-like portion passing through a side of the barrel, and a flange, said flanges paralleling

each other and being spaced a short distance apart, two pins connected to one of said flanges at diametrically opposed points and passing partly through the other flange, one of said pins passing through the opposite end of said member, and means for rotating the operating device.

3. A lock comprising a substantially cylindrical barrel and formed at opposite sides with outwardly extended portions to make elongated grooves or troughs in opposite sides of the barrel, an operating device rotatably mounted transversely of the barrel between said grooved portions, a lock bolt, a member pivotally connected at one end to the bolt and at its other end to the operating device to one side of its axis of rotation, and means for turning the operating device, said member entering one of said grooves as the same is moved in turning the operating device.

4. A lock comprising a cylindrical barrel, having openings in opposed sides of the barrel, an operating member formed of two parts, each including a cup-like portion and a flange at the free edges of the cup, said cup-like portions being rotatably mounted in said openings, one end of one of said cups being provided with an opening for an operating bar and the end of the other cup having openings for connection of a key therewith, pins between the flanges near the edges thereof, and a locking bolt operatively connected with one of said pins for projection or retraction on rotation of the operating member in opposite directions.

5. A lock, comprising a cylindrical barrel, a locking bolt mounted in the barrel for projection or retraction at one end thereof, a rotatably mounted operating device, connections between the bolt and operating device for moving the bolt longitudinally on rotation of the operating device, and a member for manually turning the operating device adapted to be inserted into one end of said device and extended different distances therein whereby said lock is adapted for different thicknesses of doors, substantially as described.

6. In a lock, a cylindrical barrel, a bolt mounted at one end thereof for projection and retraction, an operating device mounted for rotation between opposite sides of the barrel, said device being divided vertically midway between its ends, two pins extending across between the divided portions of the operating device, and a member of flat metal pivotally connected at one end to one of said pins and at its other end to the inner end of the bolt.

7. A construction containing the elements in combination defined in claim 6, combined with spring means for yieldingly holding the bolt in either projected or retracted position against accidental movement.

8. A lock comprising a substantially cylindrical barrel formed at opposite sides intermediate its ends with outwardly projecting portions to make grooves on the inner sides of the barrel, a lock bolt, a rotatably mounted operating device mounted transversely of the barrel, and means connecting the operat-

ing device and bolt for reciprocating the bolt on rotation of the operating device, said means entering one of the said grooves as the same is moved in rotating the operating device.

In testimony whereof I affix my signature.

LUCIEN A. DEXTER.
